UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

HOPPER MECHANISM.

1,001,791.

Specification of Letters Patent. Patented Aug. 29, 1911.

Application filed April 7, 1910. Serial No. 554,078.

To all whom it may concern:

Be it known that I, RICHARD LESTER WILCOX, a citizen of the United States, residing at Waterbury, in the county of New Haven and State of Connecticut, have invented certain new and useful Improvements in Hopper Mechanism, of which the following is a specification, reference being had therein to the accompanying drawings.

10 My invention relates to new and useful improvements in hopper mechanism, having particular reference to that type of hopper mechanism, wherein a plurality of blanks are thrown indiscriminately into a receptacle, and are automatically delivered therefrom in a continuous stream with all the successive blanks arranged with their shanks substantially parallel with each other, and the heads in substantially the same line.

15 It is the object of my invention, among other things, to construct a device of this character, whereby the above, and other results, will be accomplished with mechanism that is of few parts, so designed as to be 20 economically constructed and readily assembled; that will allow for the stoppage of the flow of blanks at the delivery point, when desired, without disturbing the operation of the other parts of the hopper mechanism; and have means whereby the several parts may be adjusted in relation to each other, and arranged so that access may be had to the blanks between the containing receptacle and the point of delivery.

25 To these, and other ends, my invention consists in the hopper mechanism, having certain details of construction, and combinations of parts, as will be hereinafter described, and more particularly pointed out 30 in the claims.

Referring to the drawings, in which like numerals of reference designate like parts in the several figures; Figure 1 is a side elevation of my improved device; Fig. 2 is a 45 plan view thereof; Fig. 3 is a transverse sectional view upon line A—B of Fig. 1; Fig. 4 is an enlarged view of the upper end of the chute mechanism, with a portion of the clearing mechanism in section; Fig. 5 is an 50 enlarged plan view of the lower end of the chute mechanism partly in section; Fig. 6 is a sectional view thereof upon line C—D of Fig. 5; Fig. 7 is an elevation of the chute means for lateral adjustment of the chute

plates at the receptacle end, with said plates 55 in section upon line E—F of Fig. 4; Fig. 8 is a plan view of the cover block and some of the parts adjacent thereto; Fig. 9 is a side elevation partly in section of the blade mechanism; Fig. 10 is an enlarged sectional 60 view thereof upon line G—H of Fig. 9; Fig. 11 is an enlarged sectional view thereof upon line I—J of Fig. 9; Fig. 12 is an elevation of the journal block for the clearing shaft; and Fig. 13 is a plan view of the 65 clearance wheel.

In the practice of my invention I provide a blank receptacle 1 that is preferably constructed of two separate sections secured together by screws 2 and 3, a filler block 4 being between the sections at their rear end and a cover block 5 at the front end. Movable within this receptacle, and between the sections thereof, is a blade 6, which is fixed to the arm 7 that is pivotally connected with the bracket 8 upon the stud 9. Movement is imparted to this blade from the gear 10, having a roll 11 upon one side thereof, which contacts with the fin 12 integral with the arm 7. Said gear is rotatable upon a 70 stud 13 mounted in the bracket 14, that is fixed to the bed 15 of the machine, and to which the receptacle 1 is secured by the bolts 16. Rotarily mounted in the bracket 14 is a 75 shaft 17, having a driving pulley 18 thereon, and a pinion 19, the teeth of which mesh 80 into the teeth of the gear 10, transmitting a rotary movement thereto. The means shown and described for imparting movement to the blade is only one of several ways 85 that the same may be accomplished, and I do not therefore limit myself thereto.

Separably secured to the blade 6, by the screws 72, is the lifting plate 20, having the slot 21 in its upper edge, that is closed at 95 the outer end (see Fig. 9). The top of this plate is flared inwardly for a portion of its length, forming the faces 22, and outwardly for a portion of its length, forming the faces 23. As the blade moves from the bottom of the receptacle 1 up through the mass of blanks, the said blanks lie on the lifting plate at various angles, some with their shanks in the slot 21 and their heads resting upon the top edge thereof, which is the correct delivery position, some with their shanks crosswise, and others with their shanks lengthwise of said slot but prevented 100

from entering it by reason of their contact with adjacent blanks, etc. The agitation of the blanks in the receptacle, caused by the movement of the blade therethrough, removes some of these irregularly arranged blanks and others fall off after the lifting plate is above the blanks by reason of the angular faces 22 and 23, so that when the lifting plate is in its extreme upward position those blanks with their shanks in the slot 21 slide toward the inner face of the said lifting plate, and if perchance a blank lies irregularly upon the said lifting plate, it will fall therefrom as it slides down between the inclined faces 22 onto that portion of the lifter plate where the faces 23 flare outwardly.

The numeral 24 designates the chute bracket which is adjustably secured to the receptacle 1 by the screw 25 that passes through the elongated slot 26, and adjustable upon said bracket is the slide 27 which is secured thereto by the screw 28 that passes through the slot 29.

Fixed to the bracket 24 is the chute plate 30, and to the slide 27 the chute plate 31, said chute plates projecting into the receptacle to the edge of the blade 6, as shown in Figs. 1 and 4. The outer ends of these chute plates are connected with a fixed part 32 upon the bed 15, through the brackets 33, which have a lateral adjustment upon said fixed part, by means of the screws 34 which project through the slots 35 in said brackets, and are threaded into said fixed part. These chute plates are shown as being secured to the several brackets and slides by means of the screws 36, but any other means may be used if desired. An adjustable connection is made between the brackets 33 by the screw 37, which is held against endwise movement upon one of the brackets by the collars 38 and 39 thereon, and threaded through the other bracket so that by rotation of the screw 37 either one or both of the brackets will be caused to move toward and away from each other. The open space between the chute plates is substantially the same width as the slot 21 and may be varied by moving said plates toward and away from each other, the inner end by adjustment of the slide 27 upon the bracket 24, and the outer end by adjustment of the brackets 32 toward and away from each other, as above described. The lateral position of these chute plates as a unit may also be varied by shifting the bracket 24 upon the receptacle 1, and the brackets 33 upon the fixed part 32. Pivotally connected with the cover block 5 by the pintle 40 is the cover 41, which is supported at its free end by the plate 42 secured to one of the chute plates by the stud 43 that projects through the slot 44 with a nut 45 thereon, and the stud 46 which is threaded through said cover with a jamb

nut 47, a collar 48 and a thumb nut 49 thereon, said stud passing through the slot 50 in the plate 42. Said cover is positioned to lie over the top of the open space between the plates 30 and 31, and is adjusted toward and away from said plates at the receptacle end by manipulation of the screws 3, which pass through slots 51 in the cover block, and at the other end by shifting the position of the cover plate 42 so as to vary the distance between the bottom of the slot 50 therein and the top of said chute plates. The cover 41 may be moved out of its down position to thereby expose the tops of the chute plates and the blanks therein by loosening the thumb nut 49 and swinging said cover upon its pivot mounting to the position shown by broken lines in Figs. 1 and 3, it being held in this position by the clip 52 which is fixed to the block 5, and the fingers of which enter the recesses 53 in said cover.

I have provided means for shutting off the flow of blanks from the chute, when desired for any purpose, which means comprises a stop plate 54 that is adjustably secured to the fixed part 32, by the screws 54, and having a pointed inner end made by the angular face 55. In its inward position, shown in Figs. 2 and 5, the pointed end of said stop plate is moved into and across the path of the blank between said chute plates and stops the movement of said blanks at the delivery point without affecting the movement of any of the other parts connected with said hopper mechanism and without waiting for all of the blanks in the chute to be discharged therefrom.

It is apparent that in operation this device will pick the blanks out of the receptacle and deliver them into the chute arranged in proper order, that the feeding of said blanks can be stopped instantly, and that all of the parts are both adjustable and accessible.

With the mechanism above described it is practically impossible for a blank to enter the chute without being arranged in its proper order, but for purposes of abundant caution, and to absolutely insure this result, I have provided a clearing device to remove all improperly arranged blanks. This device consists of a shaft 57 rotatable in journal blocks 58 and passing through openings 59 in the sections of the receptacle 1; a toothed wheel 60 fixed to said shaft over the ends of the guide plates 30 and 31, and having an annular groove 61 in the face thereof; companion toothed wheels 62 fixed to said shaft 57 upon either side of the toothed wheel 60 and adjacent thereto; a plate 63 adjustably secured to the block 5, having a clearance finger 64 thereon; which lies within the groove 61 of the toothed wheel 60; a sheave wheel 65 fixed to said shaft, connected by a belt 66 with a sheave wheel 67 on the shaft 17; and a hand wheel 71 fixed to the shaft 57 for 13

manually rotating the same. The journal blocks 58 are pivotally connected with the receptacle 1 by the bolts 68 and secured in their adjusted positions by said bolt and the bolts 69, which pass through slots 70.

By adjustment of the journal blocks 58 the positions of the toothed wheels 60 and 62 may be varied in relation to the chute plates 30 and 31. Rotation of the said toothed wheels with the teeth upon the underside thereof moving away from the cover block 5 prevents the entrance of any blank from the blade mechanism into the chute mechanism if the same is not in its proper position. If the blank lies at a right angle to the chute the toothed wheels 62 will knock it from the chute back into the receptacle, and if the same lies with its shank parallel with said chute the toothed wheels 60 will perform a similar function, and if, by any chance, a blank should be picked up by any of these toothed wheels, the same will be cleared therefrom and dropped back into the receptacle by reason of the clearance plate 63 and finger 64.

There are minor changes and alterations that can be made within my invention, aside from those herein suggested, and I would therefore have it understood, that I do not limit myself to the exact construction herein shown and described, but claim all that falls fairly within the spirit and scope of the following claims.

Having described my invention, what I claim as new, and desire to secure by Letters Patent, is:—

1. In a hopper mechanism, the combination with a containing receptacle; of a blade movable therein, having a blank receiving slot therein, the edge of said blade adjacent to said slot flaring inwardly from the outside thereof to said slot for a portion of its length, and outwardly from said slot for a portion of its length.

2. In a hopper mechanism, the combination with a containing receptacle; of a blade movable therein, having a slot therein, closed at one end, the edge of said blade adjacent to said slot flaring inwardly near the closed end of said slot, and outwardly from the termination of said inwardly flaring portion to the other end of said blade.

3. In a hopper mechanism, the combination with a containing receptacle; of a chute mechanism having parallel members, one of said members being adjustably connected with said receptacle, and the other member adjustably connected with said first member.

4. In a hopper mechanism, the combination with a containing receptacle; of a chute mechanism having parallel members; and means for adjusting said members in relation to said containing receptacle and to-

ward and away from each other at either or both ends.

5. In a hopper mechanism, the combination with a containing receptacle; of a chute mechanism having parallel members; means for connecting said members together and to said containing receptacle, so that the relative positions thereof may be varied toward and away from each other and as a unit in relation to said containing receptacle.

6. In a hopper mechanism, the combination with a containing receptacle; of a chute bracket adjustably connected with said receptacle; a slide adjustably connected with said bracket; and plates connected with said bracket and slide.

7. In a hopper mechanism, the combination with a containing receptacle; of a bracket adjustably connected with said receptacle; a slide adjustably secured to said bracket; companion brackets adjustably secured to a fixed part; means for moving said brackets toward and away from each other; and plates connected with said bracket, slides and companion brackets.

8. In a hopper mechanism, the combination with a containing receptacle; of a cover block adjustably connected therewith; a chute mechanism adjustably connected with said receptacle; a cover pivotally connected with said cover block; and means for separately and adjustably securing the free end of said cover to said chute mechanism.

9. In a hopper mechanism, the combination with a containing receptacle; of a chute mechanism; and means for clearing said chute mechanism of all blanks not properly arranged therein, said means comprising a toothed rotary member, and a stationary member projecting into the path of said rotary member.

10. In a hopper mechanism, the combination with a containing receptacle; of a chute mechanism; and means for clearing said chute mechanism of all blanks not properly arranged therein, said means comprising toothed rotary members of varying diameters, and a stationary member projecting into the path of said rotary member.

11. In a hopper mechanism, the combination with a containing receptacle; of a chute mechanism; and means for clearing said chute mechanism of all blanks not properly arranged therein, said means comprising a rotary shaft; means for adjusting the axial position of said shaft in relation to said chute mechanism, a clearing wheel on said shaft, and a fixed part in the path of said wheel.

12. In a hopper mechanism, the combination with a containing receptacle; of a chute mechanism; and means for clearing said chute mechanism of all blanks not properly arranged therein, said means comprising a

rotary shaft, and toothed wheels on said shaft of varying diameters and arranged in relation to said chute mechanism, whereby one of said wheels will rotate upon one side thereof and the other above the top thereof.

13. In a hopper mechanism, the combination with a containing receptacle; of a chute mechanism; and means for clearing said chute mechanism of all blanks not properly arranged therein, said means comprising a rotary shaft, toothed wheels on said shaft of varying diameters and arranged in relation to said chute mechanism, whereby one of said wheels will rotate upon one side thereof and the other above the top thereof, and a fixed member in the path of said toothed wheels.

14. In a hopper mechanism, the combination with a containing receptacle; of a chute mechanism; and means for clearing said chute mechanism of all blanks not properly arranged therein, said means comprising a shaft, a toothed wheel on said shaft having a groove in the face thereof and rotating adjacent to the top of said chute mechanism, a

fixed part projecting into said groove, and toothed wheels on said shaft upon either side of the aforesaid toothed wheel, rotating upon either side of said chute mechanism, with a portion thereof projecting below the top of said chute mechanism.

15. In a hopper mechanism, the combination with a containing receptacle; of a chute mechanism; a cover for said chute mechanism; and means for securing said cover so as to provide for its adjustment toward and away from said chute mechanism, said means comprising an adjustable plate adjacent to the end of said cover, distant from said containing receptacle, and a block having a pivotal connection with said cover, separably and adjustably secured to said containing receptacle.

In testimony whereof I affix my signature in presence of two witnesses.

RICHARD LESTER WILCOX.
